UNITED STATES PATENT OFFICE.

THEODORE J. ZOELLER, OF LOUISVILLE, KENTUCKY, ASSIGNOR TO HIMSELF, DANIEL E. DOHERTY, B. D. MATTINGLY, AND C. J. DOHERTY, OF SAME PLACE.

ELECTRIC GAS-LIGHTER.

SPECIFICATION forming part of Letters Patent No. 408,785, dated August 13, 1889.

Application filed December 10, 1888. Serial No. 293,102. (No model.)

To all whom it may concern:

Be it known that I, THEODORE J. ZOELLER, a citizen of the United States, residing at Louisville, in the county of Jefferson and State of Kentucky, have invented certain new and useful Improvements in Electric Gas-Lighters, of which the following is a specification, reference being had therein to the accompanying drawings.

10 This improvement relates to that class of electric lighting in which a taper or small light is kept continually burning, and which is increased to its full power by the motion of a valve caused by the movement of an armature of an electro-magnet; and the invention consists in the peculiar construction, arrangement, and combination of parts hereinafter more particularly described, and then definitely pointed out in the claims.

20 In the accompanying drawings, Figure 1 represents a side elevation of my improvement with parts broken away the better to show the internal mechanism. Fig. 2 is a plan with a part of the casing and burner removed. Fig. 3 is also a plan with the mechanism removed from the upper chamber. Fig. 4 is an elevation of the armature, its shaft, the valve, &c., detached. Figs. 5, 6, and 7 represent modifications.

30 Referring now to the details of construction as shown in the drawings, A represents the base, provided with a socket B to screw onto the supply-pipe in place of the ordinary burner. From one side of this socket branches out a feed-pipe C, which passes gas-tight through the base A, and also through a diaphragm D, having flanges d d projecting upward and downward, as shown in Fig. 1. Around this base and the lower flange is set 40 a cylinder E, and secured to the upper flange is a dome F, of any suitable form, from the center of which rises the burner G, which should be protected with a suitable shield or cap to prevent the taper being blown out by the wind. The dome F is fitted gas-tight to the flange of the diaphragm and forms a gas-chamber, into which gas passes from the feed-pipe C.

Between the bars A and diaphragm D is an

electro-magnet H, the pole I of which extends 50 up through a gas-tight opening in the diaphragm D.

At J is a bracket screwed to the diaphragm and carrying at its upper end a cupped screw K, between which and a similar screw K', set 55 in the base A, works a conically-ended shaft L, carrying a permanent magnet M by means of a bridge N, which is firmly secured to the shaft L and to the permanent magnet, which magnet acts as an armature to the electro-magnet H.

Between the base A and diaphragm D is a tube O, closed at the bottom, but open at the top, which allows of the use of a long shaft for the magnet M, and thus insures a steady 65 motion for the said magnet M.

Attached to the shaft is a strip forming a valve P, the free end of which carries a screw Q, whose lower end rests on the magnet M, and by screwing said screw in or out 70 the distance of the valve P from the outlet of the feed-pipe may be regulated, as the strip will spring slightly, and thus the amount of gas passing through the pipe to supply the taper will be regulated.

In some cases, instead of the screw resting on the magnet, I use the end of the screw for the valve, as shown in Fig. 7, in which case, also, the amount of gas for the taper will be regulated by turning the screw in or out.

In the modification shown in Fig. 5 the end of the feed-pipe is curved, as at c, so as to have the gas pass out horizontally, and the valve P moves to and from the same in the manner of a lift-valve, instead of moving 85 over the same, as in the style of valve shown in Figs. 1, 2, 3, and 4.

I sometimes divide the armature in two, so as to use two poles of an electro-magnet, as shown in Fig. 6. This style of armature may 90 be used either with the form of valve shown in Figs. 1, 2, 3, and 4 or that shown in Fig. 5. Both forms are shown in Fig. 6, either or both of which may be used.

Below the base are two binding-posts R, 95 through which connection of the coil of the magnet may be made with the line-wire and any suitable reversing device—such, for

instance, as that shown diagrammatically at Z.

The burner proper should be provided with a suitable protector to prevent the wind from blowing out the taper. This may be of any suitable shape. One form of protector is shown at X on Fig. 1; but I do not limit myself to this form. Suppose, now, that a series of these burners are properly connected with the service-pipe by being substituted for the ordinary burner, and that the magnets are properly connected through the binding-posts to an electrical circuit, and that this circuit is provided with a reversing apparatus by which the polarity of the current may be changed, and that several of such series of burners, &c., are connected to a suitable switching apparatus and battery of any suitable kind in a central office, and that all of the burners have been lighted by hand on commencing operations. This being done, if we send a current through the electric circuit, the electro-magnet will operate on the permanent magnet and move it in one direction or the other, according to the polarity of the current. If, for instance, the armature and valve are in the position shown in Fig. 2, with the gas on to its full power, a current of opposite polarity to that last used will cause the electro-magnet to change the position of the armature and valve, so that only sufficient gas will pass through the pipe to keep the taper burning. If, on the contrary, only sufficient gas is passing through the burner to supply the taper and a current of the reverse polarity is sent through the circuit, then the electro-magnet will cause the armature and valve-strip to assume the position shown in Fig. 2, and the full amount of the gas is allowed to escape from the feed-pipe, and the light is thus increased to its full force.

It will be understood that it requires only a momentary impulse to produce the required result, as the mechanism will remain at rest after the current is cut off, due to the attractive force of the permanent magnet. Therefore the same battery can be switched from one circuit to another to turn on or off the gas. After that it can remain at rest.

As very little friction or resistance of any kind is to be overcome, only a small battery will be needed, and a small hand-dynamo may be used in place of a battery.

It will be observed that the valve never touches the seat, but is always free from the same; hence there is no friction of the valve upon the seat, which will account for the small amount of battery-power required.

I may sometimes dispense with the valve-strip altogether and so arrange the armature that it will be over and cover or uncover the opening in the feed-pipe. In such case, of course, the armature would be both an armature and a valve. Where the armature was

used as a valve the space between it and the end of the feed-pipe might be adjusted by the screws K K' at the opposite ends of the central shaft.

Having thus shown how my invention may be practically carried out, but without limiting myself to the construction shown, I claim as new—

1. The combination, in a gas-lighter, of an electro-magnet, an armature therefor, a feed-pipe having an orifice to discharge the gas, and a valve constructed and arranged to be held in its normally-closed position contiguous to said orifice, but free from the walls thereof, and opened to allow the full force of the gas to pass through without friction between the valve and the walls of the orifice, substantially as described. 75

2. The combination, in a gas-lighter, of an electro-magnet, a permanent magnetic armature therefor, a feed-pipe having an orifice to discharge the gas, a valve held by the attraction of the permanent magnet in its normally-closed position contiguous but free from contact with the walls of said orifice, and constructed to move away from the same to admit the full discharge therefrom without friction between the walls of said orifice and the valve, substantially as described. 85

3. The combination, in a gas-lighter, of an electro-magnet, a permanent magnetic armature, a feed-pipe having an orifice to discharge the gas, and a valve moving over said orifice to partially close the same while free from contact with the walls thereof, substantially as described. 95

4. The combination, in a gas-lighter, of an electro-magnet, a permanent magnetic circular armature therefor mounted on a central shaft, a feed-pipe having an orifice to discharge the gas, and a valve connected to and moving with said armature and over said orifice, substantially as described. 105

5. The combination, in a gas-lighter, of an electro-magnet, a permanent magnetic circular armature therefor mounted on a central shaft, a feed-pipe having an orifice to discharge the gas, a valve connected to and moving with said armature, and means, as the screw Q, for regulating the amount of discharge for the taper, substantially as described. 115

6. The combination, in a gas-lighter having upper and lower chambers, of an electro-magnet set in the lower chamber, a permanent magnetic circular armature therefor working in the upper chamber and mounted on a central shaft, a tube extending into the lower chamber and surrounding the central shaft, a feed-pipe passing through the lower chamber and terminating in the upper chamber, and a valve connected to and moving with the armature and partially closing the mouth of the feed-pipe, substantially as described. 120

7. The combination, in a gas-lighter, of an 130

electro-magnet, a permanent magnetic armature therefor having its opposite poles arranged on opposite sides of one pole of the electro-magnet, a feed-pipe to discharge the 5 gas, and a valve moving with said armature and governing the emission of the gas from said feed-pipe, substantially as described.

In testimony whereof I affix my signature, in presence of two witnesses, this 6th day of December, 1888.

THEODORE J. ZOELLER.
